ABSTRACT: This composite package includes a skin-packaged article of merchandise and a carton for supporting and retaining the skin package in position during shipping or display. The carton includes an open-faced frame having a height at least as great as that of the article of merchandise so that a stack of such composite packages will be stable. Holes through the package may be provided so as to permit display of the packaged article in a hanging position.

COMPOSITE PACKAGE

CROSS REFERENCE TO RELATED INVENTION

The composite package in accordance with the present invention is especially suited to incorporate for shipping and display an article of merchandise in a "skin package" which may be formed by the process disclosed and claimed in U.S. Pat. No. 3,267,633, issued on Aug. 23, 1966 to the inventor of the composite package disclosed and claimed in the present application.

BACKGROUND OF THE INVENTION

By practicing the invention covered by the above-mentioned patent, an excellent "skin package" may be produced. As described in that patent, articles of merchandise may be positioned on a stiff backing board of heavy paperboard, or some such material, and are then disposed for covering by a film of clear thermoplastic material. A sheet of the skin-packaging film of clear thermoplastic material is clamped in a frame and is heated until it softens and becomes easy to stretch or deform. Then the clamped sheet of soft thermoplastic film is lowered over the articles and the backing board, and allowed to "drape" so that it conforms to the contours of the articles and so that it laminates with the surface of the backing board around the articles of merchandise. Suction is applied below or behind the backing board, so that the differential air pressure forces the soft thermoplastic film to drape closely about the articles of merchandise and to cling tightly and smoothly to the surface of the backing board around the articles of merchandise.

When the thermoplastic film material has been allowed to cool and has been trimmed so that it is coextensive with the edges of the backing board, the skin package *per se* is complete. However, the skin package as it stands leaves much to be desired so far as suitability for storage, shipment, and display is concerned. The edges of the skin package show the internal structure of the backing board, which may be corrugated and rather unsightly. Moreover, no satisfactory arrangement has as yet been made for hanging the skin package to display the packaged article of merchandise in a store. Still further, the skin package as it stands is not very suitable for shipment or for stacking in a neat pile because the article of merchandise located centrally on the backing board rises far above the edges of the backing board. It is apparent that skin-packaged articles of merchandise, such as kitchen faucets or spray heads, cannot be piled in a stable stack unless the outer periphery of the skin package includes some structure characterized by at least as much height as the article of merchandise located in the middle of the package.

Accordingly, it is an object of this invention to provide a composite package in which a skin-packaged article of merchandise is supported in a carton that includes a rigid frame around the article of merchandise, said frame having a height above the backing board of the skin package which is at least as great as the height of the article of merchandise above said backing board.

It is another object of the invention to provide a composite package including a carton which may easily be erected from a blank of inexpensive sheet material and which supports a skin-packaged article of merchandise in such a way that the edges of the skin package are concealed.

It is a further object of the invention to provide a composite package including a carton which protects a skin package contained therein and an article of merchandise contained in said skin package during storage, shipment, and display of said composite package.

It is still another object of the invention to provide a composite package that is suitable for supporting a skin-packaged article of merchandise to permit attractive display of the article in a hanging position, as well as horizontally or vertically on a shelf or counter.

SUMMARY OF THE INVENTION

Briefly, I have fulfilled the above-listed objects, and other objects of my invention, by using a carton blank which I cut from inexpensive sheet material such as paper board. The blank is scored so as to define therein a substantially rectangular base panel, a pair of end flaps at the respective ends of the base panel, and a pair of longitudinal flaps at the respective sides of the base panel. Each of the end flaps is subdivided by score lines into panels of which two can be erected as riser panels substantially perpendicular to the base panel, while a narrow intermediate panel takes a position substantially parallel to the base panel at the end of the carton. The longitudinal flaps are also subdivided by score lines into panels, of which two panels are riser panels which have cross flaps appended at the respective ends thereof. A pair of cross flaps appended at the respective ends of one riser panel of each longitudinal flap are each long enough to extend more than half way across the carton in its erected state. Each of these long cross flaps is provided with a slit near the outer end thereof for cooperating with a slit in a corresponding long cross flap extending from the opposite side of the carton, locking said long cross flaps together to form a transverse inner end wall of the carton. A pair of short cross flaps are appended at the respective ends of another riser panel of each longitudinal flap, and are folded to extend part way across the carton in its erected state, substantially perpendicular to the base panel. Thus the two riser panels of each end flap are spaced apart in the erected state by the cross flaps appended to the riser panels of the longitudinal flaps. This spacing apart of the riser panels of the end flaps in their erected state insures that the end walls of the carton will be characterized by enough stiffness to bear the weight of other composite packages which may be stacked thereon.

Adhesive material may be provided on longitudinal tabs of each longitudinal flap and on portions of the top surface of the base panel for helping to hold a skin package in place on the base panel and within the frame members of the carton. Holes may be formed through the base panel of the carton and through the edge of the skin package so that the composite package may be hung on bodies such as one or more hooks, which will then support the composite package by passing through respective holes in the carton and in the skin package which are in register with each other.

For a full understanding of my invention, reference is made to the following complete description of the preferred embodiments, taken in conjunction with the attached drawings.

BRIEF DESCRIPTION OF THE DRAWINGS

In the drawings:

FIG. 1 is a plan view of a composite package in accordance with my invention, with a skin-packaged kitchen faucet in place within the frame of the carton;

FIG. 2 is an end view of the composite package taken at the plane indicated by the section line and arrows marked 2-2 in FIG. 1;

FIG. 3 is a perspective view of a plurality of composite packages according to the invention, said composite packages being hung on a pair of hooks for display;

FIG. 4 is a perspective view of a plurality of composite packages according to the invention, said composite packages being stacked on one another, as for storage, shipment, or display in a horizontal position;

FIG. 5 is a fragmental transverse sectional view taken through the end wall of the carton at the plane indicated by the section line and arrows marked 5-5 in FIG. 1. The edge of the baseboard of the skin package is shown in place resting on the base panel of the carton, and retained in position by the erected end wall of the carton;

FIG. 6 is a fragmental sectional view taken through the sidewall of the carton at the plane indicated by the section line and arrows marked 6-6 in FIG. 1. Once again, the edge of the baseboard of the skin package is shown in place resting on the base panel of the carton. In this view the retention of the skin

package in position on the base panel of the carton by the sidewall of the erected carton is illustrated;

FIG. 7 is a plan view of the blank of sheet material from which the carton is to be erected; and

FIG. 8 is a developmental view showing the way in which the flaps of the blank are folded during erection of the carton.

DESCRIPTION OF THE PREFERRED EMBODIMENT

Turning to FIG. 1 of the drawings, we see a completed composite package 11 in accordance with my invention. Composite package 11 includes a skin package 13 and a carton 15 having a frame which encloses skin package 13 and a base panel 17 which is the portion of carton 15 that supports skin package 13 in the horizontal position of the carton and of the package. Skin package 13 embraces an article of merchandise such as the kitchen faucet 19 illustrated in FIG. 1. Of course, one or more reasonably small articles of any nature might be accommodated in the package. However, a skin package of this nature is particularly well adapted for the display of plumbing supplies which must be packaged in such a way that they can be seen but not damaged during examination by customers.

The thermoplastic film 21 which holds kitchen faucet 19 in place in skin package 13 is laminated intimately with the backing board 23 which constitutes the "foundation" of the skin package 13. Adhesion of thermoplastic film 21 to backing board 23 around the periphery of kitchen faucet 19 is facilitated by several techniques. One such technique depends upon maximization of the air-pressure differential which is applied to the thermoplastic film during formation of the skin package and which forces the thermoplastic film to drape closely about the article of merchandise and to cling tightly and smoothly to the surface of the backing board around the article of merchandise. When suction is applied below or behind the backing board during formation of the skin package, the air-pressure differential across the thermoplastic film is maximized if the material of the backing board is very porous and easily permeable by air. On the other hand, if the material of the backing board is not in itself very porous, or if the backing board is covered with a layer of rather nonporous material such as glazed paper, it becomes advisable to perforate any such nonporous material with holes 25 as shown in FIG. 1 of the drawings. These holes permit the air to be rapidly withdrawn from under the thermoplastic film material when the suction is applied during formation of the skin package.

Another technique which I have employed in optimizing the adhesion between the backing board and the thermoplastic film material involves preheating the backing board and the article of merchandise before the heated and softened thermoplastic film is draped over the article of merchandise during formation of the skin package. This technique drives away any moisture which may be present on or in the article of merchandise or the backing board. By this means, diffusion of some of the plastic film material into the material of the backing board is achieved, thereby producing a strong and permanent bond between the thermoplastic film and the backing board. This method of fabricating a skin package is described and claimed in my aforementioned U.S. Pat. No. 3,267,633.

In order to permit composite packages in accordance with my invention to be piled up in a stack which is stable, I prefer that the carton employed in the composite package should have end walls 27 and 29 and sidewalls 31 and 33 all of which extend at least as far above base panel 17 as does the article of merchandise such as kitchen faucet 19 in skin package 13, when skin package 13 has been locked into the carton 15. A stack of this nature is illustrated in FIG. 4 of the drawings. Moreover, in order that each of the composite packages may be strong enough to support the weight of the composite packages and of the articles of merchandise above it in the stack, I make the walls of the carton very strong. End walls 27 and 29 of the carton are especially strong because they each

include two panels which are substantially perpendicular to base panel 17 of the carton. Moreover, in order to permit composite packages according to the invention to be safely stacked without any necessity for alining them precisely over and under one another, I provide in each end of the carton a transverse narrow panel 35 which is substantially parallel to base panel 17, when the carton is erected, and which provides a bearing surface upon which the base panel of the composite package above it in the stack may rest.

10 In order to permit composite packages in accordance with my invention to be displayed in a hanging position, as illustrated in FIG. 3 of the drawings, I prefer to provide rack holes such as those shown at 37, 39, and 41 which can accommodate one or more of hooks 43 and 45 of a display rack. 15 These holes penetrate both the edge of skin package 13 and the base panel 17 of carton 15. Of course, the respective holes formed in the skin package and in the carton should be capable of alinement to permit passage of the hooks of the display rack.

It has been explained that end walls 27 and 29 of the carton are especially strong because they each include two panels which are substantially perpendicular to base panel 17 of the carton. The strength of end walls 27 and 29 is also enhanced by the presence within each of those two walls of two pairs of cross flaps, one of said pairs of cross flaps being locked together to form a transverse inner end wall. A complete description of this transverse inner end wall will be presented in the paragraphs to follow. In view of the great strength of the 20 end walls of the carton, the sidewalls may be more simply formed and may even have a sloping outer panel so as to permit printed material on the outer surface of the sidewalls to be more easily seen when the composite package is on display. An end view of the composite package showing the sloping sidewalls is presented in FIG. 2 of the drawings. In that FIG., the top line is an edge view transverse narrow panel 35, while the bottom line is an edge view of base panel 17. The sloping line at the left of FIG. 2 is an edge view of side wall 31, while the sloping line at the right of FIG. 2 is an edge view of 25 sidewall 33. The outer panel of end wall 29, which appears in full view in FIG. 2 is a first transverse riser panel 47, which is coupled directly to the end of base panel 17 through a score line in the sheet material of the blank.

30 Having discussed the completed composite package in its erected state, I shall now describe in detail the blank of sheet material and the steps followed in erecting it into a complete composite package. A description of these steps will now be more meaningful in the light of the foregoing discussion.

35 In order to avoid redundancy and to permit drawing to a larger scale, only one-half of the blank of sheet material is shown in FIG. 7 of the drawings. It will be understood that the blank is symmetrical about the center line, and that the assembly of the end of the blank which is not shown is analogous to the assembly of the end which is shown and which will now be described in detail.

40 At each end of base panel 17 is an end flap which is coupled to the base panel through a score line in the sheet material and which is subdivided by further score lines into four panels which have all been denominated as "transverse" because, in the erected carton of the composite package, these panels all run across the end of the package. The first such panel is first transverse riser panel 47, which has already been mentioned. The ends of this panel have the shape of a "dog leg" because 45 this panel should, in the erected carton, cover the ends of the sidewalls 31 and 33. Accordingly, a portion 49 of the ends of first transverse riser panel 47 are cut obliquely in order to conform to the slope of the sidewalls in the completed carton.

47 The next element of each end flap is transverse narrow panel 35, to which reference has already been made. This panel will be folded parallel to the base panel in the erected carton, and forms the load-bearing surface on which the next package in the stack may rest as shown in FIG. 4.

50 The next element of each end flap is a second transverse riser panel 51, which is substantially rectangular and which,

once again, is separated from its adjacent panels by score lines in the material of the blank. It will be understood that an alternative way to delineate the respective panels would be simply to bend the material of the blank in straight lines. However, it is convenient to score the material, and the appearance of the blank is not injured by scoring, particularly if the surface of the material that has been scored is thereafter covered with facing paper. Such facing paper may be applied to the surface of the blank which will form the outer surface of the completed composite package. The facing paper may have any desired indicia printed or otherwise formed thereon, and may be fastened to the material of the blank by means of an adhesive. Second transverse riser panel 51 in the erected carton occupies a position such that it is substantially perpendicular to the base panel. The lower edge of second transverse riser panel 51 rests on the edge of the baseboard of the skin package and helps to hold it in place, while the upper edge of second transverse riser panel 51 helps to support the load-bearing surface of transverse narrow panel 35.

The final element of each end flap is a transverse locking panel 53, which is rather narrow, and which, in the completed package, locks under the transverse inner end wall to which brief reference has already been made. Two of the corners of transverse locking panel 53 may be rounded in order to facilitate insertion of this panel 53 under the transverse inner end wall. Transverse locking panel 53 in the completed package lies substantially parallel to base panel 17 and rests on the edge of the skin package 13 held in the carton 15. Along the score line between second transverse riser panel 51 and transverse locking panel 53 may be formed a pair of locking slots 55 and 57, one at each end of the score line. If desired, the inner ends of these slots may be curved slightly toward second transverse riser panel 51 in order to facilitate locking action.

Now, at each side of base panel 17 is a longitudinal flap which is coupled to the base panel through a score line in the sheet material and which is subdivided by further score lines into three or four panels which have all been denominated as "longitudinal" because, in the erected carton of the composite package, these panels all run lengthwise of the package. The first such panel is a longitudinal narrow panel, which helps the sidewall of the carton to adapt to the width and the thickness of the backing board of the skin package accommodated within the carton. If the backing board of the skin package is slightly wider than base panel 17 of the carton, longitudinal narrow panel 59 will assume a position in the finished carton such that longitudinal narrow panel 59 extends the effective width of base panel 17. On the other hand, if the thickness of the backing board of skin package 13 is rather great, longitudinal narrow panel 59 will assume a position in the finished composite package having a substantial component perpendicular to base panel 17, thereby permitting the sloping portion of the sidewall to begin above the level of the top surface of the backing board. If the backing board of the skin package is very thin, or if the width of the backing board of the skin package is somewhat less than the width of base panel 17 of the carton, it becomes possible to dispense with longitudinal narrow panel 59, or to make this panel very narrow indeed.

The next element of each longitudinal flap is a first longitudinal riser panel 61, which is coupled to longitudinal narrow panel 59 through a score line in the material of the blank. Of course, for cartons not employing a longitudinal narrow panel 59, first longitudinal riser panel 61 is coupled directly to the side edge of base panel 17. In the finished carton 15, first longitudinal riser panel 61 is folded to form the sloping outer surface of one side of the sidewalls of the carton.

First longitudinal riser panel 61 itself is essentially rectangular in shape. However, each end of first longitudinal riser panel 61 has appended thereto a short cross flap 63 which has one inclined edge 65. In the erected carton, each short cross flap 63 is folded so as to have a transverse position within the end wall of the carton. In this position, each short cross flap 63

gives support to first transverse riser panel 47 of the end wall and helps to maintain its position substantially perpendicular to the base panel 17 of the carton, even when a heavy load is applied to the carton by other composite packages above it in a stack. When first longitudinal riser panel 61 assumes an inclined position in the finished carton, inclined edge 65 of short cross flap 63 becomes substantially parallel to the surface of base panel 17.

The next element of each longitudinal flap is a second longitudinal riser panel 67, which is coupled to first longitudinal riser panel 61 through a score line, or other equivalent demarcation in the material of the blank. In the finished carton 15, second longitudinal riser panel 67 is folded to form an inner surface of one of the sidewalls of the carton. In the erected state of the carton, second longitudinal riser panel 67 is substantially perpendicular to base panel 17, and one edge of second longitudinal riser panel 67 bears against the top surface of the skin package, tending to hold the skin package in place in the carton.

Second longitudinal riser panel 67 itself is essentially rectangular in shape. However, each end of second longitudinal riser panel 67 has appended thereto a long cross flap 69 which may have outer corners that are rounded. The length of each long cross flap 69 is such that, when the carton is in its erected state, each long cross flap can occupy a transverse position within the end wall of the carton and can extend more than half way across the carton. I prefer to form a transverse slit 71 near the outer end of each long cross flap 69 and extending approximately one-half way across the flap. In the erected state of the carton, a transverse slit 71 in a long cross flap appended to a second longitudinal riser panel 67 of sidewall 31 engages and locks with a transverse slit 71 in a long cross flap appended to a second longitudinal riser panel 67 of sidewall 33. When these two long cross flaps are locked together by pairs, one pair in each end wall, they cooperate to form within each end wall a transverse inner end wall which greatly strengthens the end wall and directly supports second transverse riser panels 51 of the end walls in their respective positions substantially perpendicular to base panel 17.

The final element of each longitudinal flap is a longitudinal tab 73, which is coupled to second longitudinal riser panel 67 of each longitudinal flap through a score line in the material of the flap. In the finished carton 15, longitudinal tab 73 is folded under the sidewall so that one surface of longitudinal tab 73 is parallel to, and in contact with, the top surface of the edge of the skin package 13 accommodated within the carton. The surface of longitudinal tab 73 which is to be in contact with skin package 13 may have applied thereto an adhesive which will help to retain the skin package in place within the carton and which will also assist in maintaining the composite package in its firmly assembled state during storage, shipment, and display. As a further aid in maintaining the composite package in its firmly assembled state, base panel 17 of the carton may have applied thereto a pair of strips of adhesive 75 which bear against the under surface of the backing board of the skin package in the completed composite package. If desired, two of the corners of each longitudinal tab 73 may be rounded in order to facilitate insertion of the longitudinal tabs under the sidewalls of the carton.

Having described in detail the structure of the blank from which the carton 15 of the composite package 11 is erected, I shall now further elaborate on the steps of erection of the carton, as illustrated in FIGS. 5, 6, and 8 of the drawings.

In erecting a carton for the composite package according to my invention, the first step is to place on a flat surface a blank as described in the foregoing paragraphs. It is assumed that the blank has already been scored or otherwise marked to define the various panels of the respective end flaps and longitudinal flaps of the blank. The blank should be placed so that its upper surface is the surface which will become the inner surface of the carton in its erected state. The second step is to bend the end flaps and the longitudinal flaps upward and inwardly so that a bend is made at each score line. The short cross flaps 63

should be bent upwardly and inwardly, but the long cross flaps 69 should be bent outwardly and upwardly.

Next, the completed skin package 13 should be placed on base panel 17 of the carton in such a way that the skin package is properly centered on the base panel. Then the respective pairs of long cross flaps 69 should be moved so as to cross over the ends of the skin package and so that the outer ends of the long cross flaps of each pair approach each other. This motion of the long cross flaps will cause the longitudinal panels of the blank to be substantially erected, forming the sidewalls of the carton. The transverse slits 71 of the respective long cross flaps of each pair should then be locked together to form the transverse inner end walls of the carton. Next, the short cross flaps 63 should be oriented in a transverse direction so as to contribute further internal structure to the end walls of the carton.

Now, the longitudinal tabs 73 should be carefully located and pressed in place atop the upper surface of the respective side edges of the skin package 13 in such a way that the second longitudinal riser panels 67 are perpendicular to base panel 17 of the carton 15. Then, the end flaps of the carton should be bent upwardly and inwardly, and the second transverse riser panels should be bent downwardly within the frame of the carton.

Finally, the transverse locking panels 53 should be inserted under the transverse inner end walls and in contact with the upper surface of the respective ends of the skin package in the carton. The composite package is then complete when the transverse locking panels have been locked in place by means of locking slots 55 and 57, and when the first transverse riser panels 47 and the second transverse riser panels 51 have been adjusted so as to be perpendicular to the base panel 17.

There is great latitude in choice of a material for the blank from which carton 15 is to be erected. Inasmuch as the backing board of the skin package 13 is usually quite stiff, the carton need not necessarily be formed from such stiff material. I prefer to employ in my cartons ordinary paper board faced on its outer surface with semi-glossy paper that has been printed in color to describe the contents of the composite package. However, I recognize that various other sheet materials might be employed in the blanks from which cartons in accordance with my invention are to be erected. I also recognize that various other changes might be made in the configuration of the package and in the steps of erection without departing from the principles of my invention. Accordingly, I do not wish to be limited to the precise details of the disclosure which I have set forth in the foregoing paragraphs.

I claim:

1. A composite package comprising a skin package and a carton for supporting and retaining said skin package, said carton being formed from a blank including a substantially rectangular base panel, a first end flap at one end of said base panel, a second end flap at the other end of said base panel, a first longitudinal flap at one side of said base panel, and a second longitudinal flap at the other side of said base panel, each of said end flaps including in sequential arrangement coupled to an end of said base panel a first transverse riser panel, a transverse narrow panel, a second transverse riser panel, and a transverse locking panel, each of said longitudinal flaps including in sequential arrangement coupled to a side of said base panel at least a first longitudinal riser panel, a second longitudinal riser panel, and a longitudinal tab, said second longitudinal riser panel carrying at each end thereof a long cross flap, a free end of each said long cross flap carried by said second longitudinal riser panel of said first longitudinal flap being coupled during erection of said carton to a free end

of a long cross flap carried by said second longitudinal riser panel of said second longitudinal flap forming a transverse inner end wall of said carton, an end flap at each end of said base panel being folded during erection of said carton, said first and second transverse riser panels being perpendicular to said base panel while said transverse narrow panel overlies said transverse inner end wall, and said transverse locking panel of each end flap being inserted under one of said transverse inner end walls locking said carton in its erected state.

10. 2. A composite package in accordance with claim 1 in which each of said first longitudinal riser panels of said carton carries at each end thereof a short cross flap, each such short cross flap being contiguous to a first transverse riser panel of one of said end flaps, and said short cross flap being perpendicular to said base panel.

15. 3. A composite package in accordance with claim 1 in which locking slits are formed between said second transverse riser panel and said transverse locking panel near the respective ends thereof.

20. 4. A composite package in accordance with claim 1 in which each of said first longitudinal riser panels is coupled to a side of said base panel through a longitudinal narrow panel.

25. 5. A composite package in accordance with claim 1 in which adhesive material is applied to one surface of said longitudinal tab for causing said surface of said longitudinal tab to adhere to said skin package when said skin package is supported by said carton and when said carton is in its erected state.

30. 6. A composite package in accordance with claim 1 in which adhesive material is applied to portions of the surface of said base panel to facilitate adhesion between said portions of said base panel and said skin package.

35. 7. A composite package in accordance with claim 1 in which said long cross flaps have transverse slits formed near the ends thereof to permit coupling between respective long cross flaps carried by said second longitudinal riser panel of said first longitudinal flap and respective long cross flaps carried by said second longitudinal riser panel of said second longitudinal flap.

40. 8. A composite package in accordance with claim 1 in which respective opposite edges of said skin package are embraced between said base panel and respective longitudinal tabs of said carton in their erected positions.

45. 9. A composite package in accordance with claim 1 in which at least one hole is formed through an edge of said skin package and through said base panel of said carton to permit said composite package to be supported by a body that passes through said holes.

50. 10. A composite package in accordance with claim 1 in which adjacent panels of said blank are delineated by score lines formed in the material of said blank.

55. 11. A composite package in accordance with claim 1 in which each of said first longitudinal riser panels in its erected position forms an angle other than 90° with said base panel, while each of said second longitudinal riser panels in its erected position is substantially perpendicular to said base panel.

60. 12. A composite package in accordance with claim 1 in which said blank is formed from paper board material.

65. 13. A composite package in accordance with claim 1 in which said blank is formed from paper board material faced with a layer of paper.

14. A composite package in accordance with claim 1 in which said skin package includes an article of merchandise supported by a backing board and held in place by a layer of plastic film bonded to the edges of said backing board around as said article of merchandise.
